(57) **CLAIM**

The ornamental design for a tumbler with lid, as shown and described.

DESCRIPTION

FIG. 1 is a top front perspective view of a tumbler with lid, showing our new design;

FIG. 2 is a top rear perspective view of the tumbler with lid of FIG. 1;

FIG. 3 is a bottom rear perspective view of the tumbler with lid of FIG. 1;

FIG. 4 is a top view of the tumbler with lid of FIG. 1;

FIG. 5 is a bottom view of the tumbler with lid of FIG. 1;

FIG. 6 is a right side view of the tumbler with lid of FIG. 1;

FIG. 7 is a left side view of the tumbler with lid of FIG. 1;

FIG. 8 is a front view of the tumbler with lid of FIG. 1; and,

FIG. 9 is a rear view of the tumbler with lid of FIG. 1.

The broken lines in the drawings depict portions of the tumbler with lid that form no part of the claimed design.

1 Claim, 8 Drawing Sheets
